UNITED STATES PATENT OFFICE.

JOHN WOLF, OF ST. LOUIS, MISSOURI.

WALL-TRUNK.

SPECIFICATION forming part of Letters Patent No. 626,953, dated June 13, 1899.

Application filed March 9, 1899. Serial No. 708,398. (No model.)

To all whom it may concern:

Be it known that I, JOHN WOLF, a citizen of the United States, residing at St. Louis, State of Missouri, have invented certain new and useful Improvements in Wall-Trunks, of which the following is a full, clear, and exact description, reference being had to the accompanying drawings, forming a part hereof.

My invention has relation to improvements in trunks; and it consists in the novel arrangement and combination of parts more fully set forth in the specification and pointed out in the claims.

In the drawings, Figure 1 is a middle longitudinal vertical section of the trunk, showing one side open and the other closed; and Fig. 2 is a side elevation with one of the lids thrown open.

The object of my invention is to construct a wall-trunk—that is to say, a trunk provided with a top hinged in such manner that the same may open when the trunk is set close to a wall, it being understood that the prevailing construction of trunks necessitates their being moved a suitable distance from the wall to enable the hinged top or cover to open.

A further object is to arrange the top tills of the trunk in such manner as to permit the top to open and close with perfect freedom, to provide a special form of securing-strap, and to improve the same in minor particulars, better apparent from a detailed description of the device, which is as follows:

Referring to the drawings, 1 represents the body of the trunk, and 2 the lids hinged adjacent to the upper edges of the end walls thereof, the lids thereby swinging in a plane parallel to the length of the trunk or parallel to the wall against which the trunk may be placed. When the lids are closed, the inner end walls 2' thereof close contiguous to one another, as is obvious, the lower edges thereof coming contiguous to the upper surface of the transverse ledges or strips 3, secured along the outer terminal walls of the inner tills 4, hinged along the inner surfaces of the walls of the trunk adjacent to their upper edges and adapted to swing to an open position in the same direction as the lids. The strips 3 serve to stiffen the outer end walls of the tills 4, and when the latter are closed the strips practically abut against one another,

thereby insuring stiffness to the structure when the parts are closed. The tills 4 practically rest when folded to their closed position along the upper edge of the intermediate till 5, supported on the side strips 6, as usual. The side walls of the lids, as is usual, lap over the upper edges of the body of the trunk, as best seen in Fig. 2, and the free swinging edge of one of the lids overlaps the adjacent edge of the opposite lid when the same are closed, as also apparent from the dotted position of one of the lids in Fig. 2, the overlapping side edge having secured thereto a suitable latch 7, which may be locked within a socket 8, secured to the vertical wall of the body portion opposite said latch when the lid is in its closed position. Disposed on each side of the socket 8 and secured to the body of the trunk is a strap 9, which is reinforced adjacent to its fixed end by a metallic strip 10, the latter by its stiffness serving at the same time to retain the lower position of the strap in a raised position ready to be seized by the person packing the trunk. The end of the strap 9 is provided with a loop 11, which is adapted to be coupled to the adjacent end of a strap 12, adapted to encompass the lids and secured at its opposite end to the body portion on the opposite wall by a buckle (not shown) or in any mechanical manner known to the trade.

While I have herein shown a sectional lid composed of two parts, it is obvious that I may substitute a single lid hinged at one end of the body portion without departing from the spirit of my invention.

The outer adjacent walls 4' of the hinged tills 4 incline away from each other from bottom to top, thereby leaving a clear space for the adjacent end walls 2' of the lids and permitting the latter to close over the tills without obstruction.

In Fig. 2 of the drawings I have shown on the left of said figure the loop 11 of the strap 9 uncoupled from the strap 12, the strap 9 having dropped down and being shown shortened in said view; but on the right of said figure I have shown the strap 9 brought over the lid, (the coupling between the strap 12 and loop being effected on top of the lid, as the strap 12 is adjustable,) the strap 12 not being shown on that side of the figure.

Having described my invention, what I claim is—

1. A trunk comprising a body portion, a lid hinged at each end thereof and adapted to swing in a plane parallel to the length or face of the trunk, a till hinged at each end and swinging parallel to the lid, the adjacent free end walls of the tills being separated when in their closed position, to receive the adjacent end walls of the lids, substantially as set forth.
2. A trunk comprising a body portion, a lid hinged at each end thereof and adapted to swing in a plane parallel to the length or face of the trunk, a till hinged at each end and swinging parallel to the lid, transverse abutting strips disposed along the free end walls of the tills, said strips being disposed contiguous to the lower edges of the adjacent end walls of the lids when the parts are closed, substantially as set forth.
3. A trunk comprising a body portion, a lid

hinged at each end thereof and adapted to swing in a plane parallel to the length of the trunk, a till hinged at each end along the inner surface of the end wall, and swinging parallel to the lid, the free end walls of the tills inclining away from each other from bottom outwardly, a transverse strip carried by the outer surface of each inclined wall, said strips being adapted to abut against one another, an intermediate till immediately below the hinged tills, the free edge of one lid overlapping the adjacent edge of the opposite lid when the latter are closed, a locking-latch carried by said overlapping portion on the side of the trunk, and a socket for said latch carried by the body portion, substantially as set forth.

In testimony whereof I affix my signature in presence of two witnesses.

JOHN WOLF.
